METHOD OF AND APPARATUS FOR HANDLING TUBULAR KNITTED FABRIC

Jules G. Walter and Samuel Cohn, New York, N. Y., assignors to Sameco Holding Corporation, New York, N. Y., a corporation of New York

Application April 10, 1947, Serial No. 740,600

29 Claims. (Cl. 26—1)

1

This invention relates to the handling of tubular textile fabric, and particularly to a method of and apparatus for slitting and sewing fabrics carrying stripes or designs to bring the stripes, for example, into register at the sewed edge.

In knitting tubular fabric, the threads are introduced from a plurality of spools and the stitches proceed in a helical fashion. With the addition of spools, the pitch of the helix becomes greater. In the high speed machines now in common use and employing many spools, the pitch is quite considerable. The effect is not particularly apparent in fabrics of uniform color. However, in the manufacture of striped fabrics or fabrics carrying other designs such as are now commonly used for the production of sport shirts, dresses and other garments, the helical pattern introduces serious difficulty. The pattern can be demonstrated readily by beginning at one end of a length of the fabric and cutting along the line of a stripe. The cut will terminate at the opposite end of the length of the fabric, which will be reduced to a single elongated ribbon.

As the result of this condition, which is inherent in the product of tubular knitting machines, the manufacturer of garments meets with difficulty in cutting the material. Since the ends of the stripes on opposite sides of one edge of the flattened tubular fabric do not register, the pieces cut from the material in the preparation for manufacture of garments cannot be matched properly at seams and around the shoulders and collar portions of the garment.

It is the object of the present invention to provide a commercially practicable method of and apparatus for slitting fabric, automatically registering the design at one edge and sewing the edge so that the design on both sides of the fabric is uniform.

A further object of the invention is the provision of a simple, effective and practical machine in which the tubular fabric is fed, slit along one edge, automatically adjusted to cause the design to register, and sewed in a continuous operation at relatively high speed.

Another object of the invention is the provision in a machine of the type described of means for adjustably spreading the fabric while the machine is in operation.

Another object of the invention is the provision in a machine of the type described of means for eliminating curling edges of the fabric as the edges approach the sewing operation.

Other objects and advantages of the invention will be apparent as it is better understood by

2

reference to the following specification and accompanying drawing, in which:

Fig. 1 is a plan view of a machine adapted for the practice of the invention, certain parts being omitted for the purpose of clarity;

Fig. 2 is a side elevation of the structure shown in Fig. 1;

Fig. 3 is a front elevation of the structure shown in Fig. 1;

10 Fig. 4 is an enlarged plan view of a portion of the machine;

Fig. 5 is a section on the line 5—5 of Fig. 4;

Fig. 6 is a section on the line 6—6 of Fig. 4;

15 Fig. 7 is an enlarged sectional view illustrating the operation of the belt which straightens the edges of the fabric;

Fig. 8 is a plan view of a modified form of the machine;

Fig. 9 is a section on the line 9—9 of Fig. 8;

20 Fig. 10 is a partial plan view illustrating another modification of the machine; and

Fig. 11 is a diagrammatic view illustrating the operation of the machine as shown in Fig. 10.

In carrying out the present invention, the 25 knitted tubular fabric in flattened condition is fed to a driven roll which introduces the fabric to the machine at a predetermined rate. This rate is governed by the tension on the fabric which must be maintained substantially constant.

30 Control is effected by a dancer roll resting upon the fabric which in turn, through a variable speed mechanism hereinafter described, modifies the speed of the driven roll to maintain the feed at the desired rate.

35 The tubular fabric then passes over a spreader consisting of a frame having guide bars which engage opposite edges of the tubular fabric. The right-hand guide bar is fixed to align the edge of the fabric with the cutter and other mechanism.

40 The opposite guide bar is mounted upon slid able rods with connections permitting manual adjustment to the width of the fabric being treated. After initial adjustment, the movable guide bar can be shifted while the machine is in operation to apply the desired transverse tension

45 and maintain the right-hand edge of the flattened fabric in the desired position for the operations which are performed thereon.

50 As the fabric moves over the spreader, the right-hand edge thereof is drawn into contact with a cutter which slits the folded edge of the fabric. This leaves two free edges of the upper and lower layers of fabric at which, for reasons already noted, the stripes do not register. The

55

word "stripes" hereinafter includes other designs on the fabric.

As the fabric continues to move forwardly, the upper layer is formed into a loop, the size of which is adjustable, depending upon the pitch of the helix formed by the stripe in a particular fabric. By adjusting the loop, the stripe on the upper layer is brought into registry with the stripe on the lower layer. One method of forming the loop is to provide two rollers extending diagonally over the edge of the fabric on a pivoted support which permits universal adjustment through means provided for that purpose. The adjusting means enables the operator to modify the size of the loop so as to bring the stripes into registry on the two free edges of the fabric.

It is a peculiarity of knitted fabric that, upon cutting, the edges immediately curl. In order to again sew the edges without too much loss of fabric, it is necessary to uncurl them continuously as they advance. This result is readily accomplished by means of a short belt running upon pulleys and driven from the driving mechanism of the machine. The belt is preferably circular in cross-section and is made of rubber or some other suitable friction material. One run of the belt extends through a housing so that it does not engage the fabric. The other run engages the rolled edges of the fabric as the latter advances and, because the direction of movement of the belt is toward the edges, they are unrolled and flattened in readiness for sewing.

The sewing operation is effected by a standard sewing head, the details of which form no part of the present invention. Preferably a sewing head having an edge trimmer and adapted to produce a whipstitch is employed, and the seam is made closely adjacent the free edges of the fabric, so that there is little waste of material.

From the sewing unit the fabric passes off the end of the spreader which is preferably flattened at this point so that the sewed edges and the stripes on both sides of the fabric adjacent thereto are visible to the operator. By observing the fabric as it leaves the spreader, the operator can determine readily whether or not the stripes on the opposite sides of the fabric are matched. If, for any reason, after setting the machine, the stripes do not register, a simple adjustment varying the size of the loop in the upper layer of fabric will shift the stripes on that layer into registry with the stripes on the lower layer, and the operation may be continued without stopping the machine.

The apparatus as described permits continuous slitting and adjustment of the stripes on the two layers of fabric so that they register at the sewed edge. Since they are already in register at the opposite edge, the distortion due to the helical arrangement of the stitches is completely eliminated. The fabric, when re-rolled at the completion of the operation, is ready for the garment cutter, who no longer meets any difficulty in cutting patterns from the fabric in which the stripes can be satisfactorily matched.

Referring to the drawing, 5 and 6 indicate side frames which support the elements of the machine. The roll of tubular fabric 7 is supported in any suitable manner, preferably upon a plurality of rollers 8 mounted in brackets 9 at the bottom and at one end of the frame members 5 and 6. The fabric passes upwardly over a roller 10, preferably having a roughened surface supported in brackets 11 and adapted to be driven by

a V-belt pulley 12 actuated as hereinafter described. The fabric then loops under a dancer roll 13 mounted on arms 14 secured to a shaft 15 which is pivoted in brackets 16 on the frames 5 and 6. A bell crank 17 is mounted on the shaft 15 and carries variable speed V-belt pulleys 18 and 19, the function of which is hereinafter described. The dancer roll 13 serves the purpose of regulating the peripheral speed of the roller 10 in accordance with the tension on the fabric so that the tension is maintained uniform during the operation.

The fabric passes from the dancer roll 13 over an idler roll 20 supported on a bracket 21 and is then distended by spreaders 22 and 23, being supported by an idler roll 24 on a bracket 25. The spreaders are adapted to spread the fabric laterally at a uniform transverse tension. The spreader 22 is fixed, while the spreader 23 is supported on a rod 26 extending through a tubular member 27 to the side of the machine. The rod 26 may be adjusted laterally of the machine and held in the desired position by a thumbscrew 28 or other similar device.

The spreaders 22 and 23 are further supported by a roller 29 extending transversely of the machine, and the fabric, after passing through the machine, is wound upon a mandrel 30 supported between vertical guide bars 31 at the end of the machine. The roll of fabric on the mandrel 30 is actuated by a roller 32 supported on a shaft 33 and adapted to be driven by a V-belt pulley 34 in the manner hereinafter described.

Mounted on two transverse rods 35 extending between the frames 5 and 6, is a motor 37 having a shaft 38 and carrying a circular cutting knife 39 which revolves continuously during the operation of the machine and slits one edge of the tubular fabric, thus affording an upper and a lower layer. As the fabric advances, the upper layer is looped over a roller 40 and under a roller 41 (see particularly Fig. 4). The rollers 40 and 41 are mounted on spindles extending from a bracket 42 which is pivotally mounted on a shaft 43 mounted in a bracket 44 carrying the gear 45. The gear meshes with a pinion 46 on the spindle 47 carrying a knurled hand wheel 48. By manually operating the knurled wheel 48, the angular position of the rollers 40 and 41 may be adjusted as indicated by the arrow in Fig. 5, to increase or decrease the loop which is formed in the upper layer of the fabric. The size of the loop determines the relative adjustment of the upper layer of fabric with reference to the lower layer, causing the stripes 51 on the upper layer to be drawn rearwardly to a sufficient extent so that they register with the corresponding stripes on the lower layer, as indicated particularly at the right hand end of Fig. 5. This adjustment avoids the difficulty resulting from the helical form of the stripes in the fabric as initially knit.

After the loop has been formed in the manner described, the two layers of fabric converge. The upper layer is engaged by a plate 52 pivoted at 53 on a bracket 54 and pressed downwardly by a spring 55. The tension of the spring 55 can be adjusted by means of a screw 56. The lower layer of fabric is forced upwardly by a spring plate 57 secured to a bracket 58.

When a knitted fabric is slit in the manner hereinbefore described, the edges immediately curl. It is necessary to straighten the fabric. For this purpose, a belt 59 is supported on pulleys 60 and 61. The pulley 61 is splined on a stub-

shaft 62 carrying a gear 63 which is driven by a gear 64 on a shaft 65, so that the belt follows the direction of the arrows on Fig. 4. The pulley 61 is supported by a spring 66 and is adjustable by means of a screw 67 supported in a bracket 68 and having a notched handwheel 69 which is engaged by a dog 70. Slight vertical adjustments of the belt 59 are thus made so that it will properly engage the fabric. The left-hand run of the belt 59 is covered by a guard plate 71 so that it does not engage the fabric. The right-hand run, as shown particularly in Fig. 7, engages the fabric between the plates 52 and 57, forcing the edges outwardly and into alignment so that they are no longer curled. The pulley 60 may be supported on a rod 72 which is mounted in a collar 73 and adjustable by means of a set screw 74 so that the proper tension of the belt 59 may be maintained.

The fabric, with its free edges in alignment and with the stripes 51 properly aligned as the result of the formation of the loop in the upper layer, passes to the sewing machine 75 which is adapted to be driven in the manner hereinafter described. The sewing machine, as a unit, forms no part of the present invention. Any standard machine may be used for the purpose. A machine adapted to produce a whipstitch is preferably employed. The fabric with the free edges stitched together leaves the sewing machine and is rerolled as hereinbefore described.

Any suitable driving mechanism may be employed. One form of drive suitable for the machine is illustrated in which an electric motor 76 is suitably mounted beneath the frame and carries a variable speed V-belt pulley 77. Pulleys of the type described are well known in the art, and the details thereof form no part of the present invention. Consequently such details will not be described. A belt 78 connects the pulley 77 with the pulley 79 on a shaft 80 which is supported in brackets 81 suspended from a shaft 82 which extends transversely of the machine. The shaft 80 carries a second variable speed V-belt pulley 83 similar to the pulley 77 which is connected by a belt 84 to a V-belt pulley 85 on the main drive shaft 86.

To vary the speed of the machine, the brackets 81 are adapted to be shifted laterally by means of a hand wheel 87 on a shaft 88 carrying a bevel gear 89 which meshes with the bevel gear 90. The latter is connected to the shaft of a worm wheel 91 engaging a worm 92 on the shaft 82. Thus, by shifting the position of the shaft 80, by swinging the brackets 81, the relative pitch of the various pulleys may be modified to secure the desired speed of operation. Any other variable speed drive may be employed to actuate the main drive shaft 86.

The main drive shaft carries at one end a V-belt pulley 93 which is connected by a V-belt 94 to the pulley 18. A V-belt 95 connects the pulley 19 to the pulley 12. The pulleys 18 and 19 are of the variable speed type well known in the art. The shifting of the bell crank 17 by slight variations in the tension of the fabric modifies the relative pitches of the pulleys 18 and 19 and hence the speed of the pulley 12. This minor adjustment occurs continuously during the operation of the machine to maintain uniform tension on the fabric.

A V-belt pulley 96 on the main drive shaft 86 is connected by a V-belt 97 to a V-belt pulley 98 on the shaft 65, thus driving the belt 59 as hereinbefore described. A V-belt pulley 99 is con-

nected by a V-belt 100 to a pulley 101 which is mounted on a bracket 102 pivoted at 103 on the frame of the machine. A hand-wheel 104 is mounted on the frame of the machine and provided with a screw 105 engaging the bracket 102 to adjust the tension of the belt 100. A V-belt 106 engages a pulley 107 and a pulley 108 which is connected to the drive shaft of the sewing machine, thus maintaining operation of the latter while the machine is running. The pulleys 101 and 107 are of the variable speed type, so that adjustment of the hand-wheel 104 modifies the speed of the sewing machine as required to effect the desired operation.

A pulley 109 on the main drive shaft 86 is connected by a belt 110 to a pulley 111 supported on a bracket 112 pivoted at 113. A hand-wheel 114 is mounted on the frame of the machine and provided with a screw 115 engaging the bracket 112. A pulley 116 is connected by a belt 117 to the pulley 34 on the shaft 33. The pulleys 111 and 116 are of the variable speed type. Thus, by manipulating the hand-wheel 114, the speed of the rewind roll 32 may be adjusted.

As indicated particularly in Figs. 1, 2, and 5, the spreader 22 has a flattened plate portion 118 at its end. As the fabric passes over this end of the spreader, it is spread vertically. Thus the operator may determine at a glance whether or not the stripes 51 are properly registered. If for any reason the stripes do not register, a slight adjustment of the knurled wheel 48 modifying the size of the loop will bring the stripes into adjustment without stopping the machine. In actual operation, when the machine has once been adjusted to a particular fabric, substantially no modification is necessary during the run because in knitting the fabric the stripes follow a uniform helical pattern which does not vary materially. Since the tension on the fabric is maintained automatically, in the longitudinal direction, and is fixed in the lateral direction, the adjustment of the loop to bring the stripes at the opened edge into registry should maintain that relation throughout the run of the particular fabric.

In Fig. 8, a modified form of the invention is illustrated. Since the parts are generally the same, the same reference numerals are applied and the description hereafter embodies only the essential changes in the mechanism, which are concerned primarily with the means for spreading the fabric laterally. Thus, spreaders 119 and 120 are supported similarly to the spreaders 22 and 23. The spreader 119 is, however, provided with a driving belt 121 supported on rollers 122 and 123 and also with a roller 124. The edge of the fabric is engaged between the belt and roller 124 and a roller 125 supported on a spindle 126. The spindle 126 is driven by a worm 127. Similarly, the spreader 120 is provided with a belt 128 supported on rollers 129 and 130 and also with a roller 131. The edge of the fabric is engaged between the belt and roller 131 and a roller 132 supported on the spindle 133 which is likewise driven by the worm 127. Thus a positive drive is afforded to draw the fabric over the spreader and advance it through the mechanism.

The worm 127 is driven by a V-belt pulley 134 which is connected by a V-belt 135 to a V-belt pulley 136 on the drive shaft 137. The latter shaft carries a V-belt pulley 138 which is connected by a V-belt 139 to a pulley 140 on the shaft of a motor 141. The V-belt pulley 142 on the shaft 137 is connected by a V-belt 143

to a V-belt pulley 144 on a shaft 145. At the opposite end of the shaft is a pulley 83, as in the preceding embodiment of the invention, which is adapted to drive the fabric feeding mechanism at a uniform tension in the manner hereinbefore described.

Lateral adjustment of the spreaders 119 and 120 is accomplished by means of a sleeve 146 and screw 147 with an adjusting collar 148. The position of the worm shaft 127 is also adjustable by means of a screw 149 which is actuated by a knurled hand-wheel 150.

The respective drives for the edge-straightening belt, sewing machine and wind-up roll are identical with the previous embodiment of the invention and need not be described again in detail.

Referring to Figs. 10 and 11, another embodiment involving the same principle but including a modified form of spreader is illustrated. Only the essential changes in the mechanism will be described. The spreader, in this case, consists of a floating loop 151 which is mounted between rollers 152 and 153 and carries a roller 154 at its forward end where it engages rollers 155 and 156 with the fabric disposed between the respective rollers. The rollers 155 and 156 are driven in any suitable manner and are adapted, therefore, to draw the fabric forwardly as it is fed and to deliver it to the wind-up mechanism indicated by the roller 157 and the roll of fabric 158 on the mandrel 159. Since the remaining elements of the structure are substantially as described in the first embodiment of the invention, the same reference numerals are employed, and further description will be unnecessary.

The mechanism in the three modifications hereinbefore described and with other variations which will readily occur to one skilled in the art permit the operation of a method of handling striped knitted fabrics in which the fabric is fed continuously, slit at one edge, looped in one layer to adjust the free edges of the fabric relatively and longitudinally, so that the stripes on the upper and lower layers are brought into alignment, and thereafter stitched to again afford a tubular fabric in which the stripes are aligned at both edges, thus avoiding the difficulties heretofore met in cutting such fabrics for manufacture into garments. The method is capable of application through a variety of mechanical devices, its essential novelty residing in the formation of the loop in one of the layers of fabric to permit longitudinal adjustment relatively of the free lateral edges. The method as well as the apparatus as hereinbefore described performs an entirely novel function in that it has not been practicable heretofore to continuously and satisfactorily cut and re-form striped tubular knitted fabrics with the stripes properly registered at both edges of the fabric and thus avoid the result of the normal, helical arrangement of the stripe in the fabric.

Various changes may be made in the details of procedure and in the apparatus employed without departing from the invention or sacrificing the advantages thereof.

We claim:

1. The method of modifying flattened tubular knitted fabrics to avoid the helical pattern thereof which comprises, advancing the flattened fabric continuously, slitting the fabric at one side to provide separated edges, causing one layer of the fabric to follow an elongated path with ref-

erence to the path of the opposing layer to bring the design on the separated edges into register, and sewing the separated edges so that the fabric is restored to tubular form.

5. The method of modifying flattened tubular knitted fabrics to avoid the helical pattern thereof which comprises, advancing the flattened fabric continuously while maintaining substantially uniform longitudinal and transverse tension on the fabric, slitting the fabric at one side to provide separated edges, causing one layer of the fabric to follow an elongated path with reference to the path of the opposing layer to bring the design on the separated edges into register, and sewing the separated edges so that the fabric is restored to tubular form.

3. The method of modifying flattened tubular knitted fabrics to avoid the helical pattern thereof which comprises, advancing the flattened fabric continuously, slitting the fabric at one side to provide separated edges, causing one layer of the fabric to follow an elongated path with reference to the path of the opposing layer to bring the design on the separated edges into register, and sewing the separated edges so that the fabric is restored to tubular form.

4. The method of modifying flattened tubular knitted fabrics to avoid the helical pattern of the design thereon which comprises, advancing the flattened fabric continuously, slitting the fabric at one side to provide separated edges, relatively adjusting the edges of the fabric to bring the design on the separated edges into register, progressively uncurling said edges and sewing them together while maintaining them uncurled and in alignment so as to give the fabric a tubular formation.

40. 5. The method of modifying flattened tubular knitted fabrics to avoid the helical pattern of the design thereon which comprises, advancing the flattened fabric continuously while maintaining substantially uniform longitudinal and transverse tension on the fabric, slitting the fabric at one side to provide separated edges, relatively adjusting the edges of the fabric to bring the design on the separated edges into register, progressively uncurling said edges and sewing them together while maintaining them uncurled and in alignment so as to give the fabric a tubular formation.

6. The method of modifying flattened tubular knitted fabrics to avoid the helical pattern of the design thereon which comprises, advancing the flattened fabric continuously, slitting the fabric at one side to provide separated edges, relatively adjusting the edges of the fabric to bring the design on the separated edges into register, adjusting the length of the elongated path to compensate for variations in register, progressively uncurling said edges and sewing them together while maintaining them uncurled and in alignment so as to give the fabric a tubular formation.

65. 7. The method of modifying flattened tubular knitted fabrics to avoid the helical pattern of the design thereon which comprises, advancing the flattened fabric continuously, slitting the fabric at one side to provide separated edges, causing one layer of the fabric to follow an elongated path with reference to the path of the opposing layer to bring the design on the separated edges into register, progressively uncurling the edges of the fabric, aligning the edges while uncurled, trimming said uncurled edges of the fab-

ric, and securing the edges together to form a tube while maintaining the edges uncurled and in alignment.

8. The method of modifying flattened tubular knitted fabrics to avoid the helical pattern of the design thereon which comprises, advancing the flattened fabric continuously while maintaining substantially uniform longitudinal and transverse tension on the fabric, slitting the fabric at one side to provide separated edges, causing one layer of the fabric to follow an elongated path with reference to the path of the opposing layer to bring the design on the separated edges into register, progressively uncurling the edges of the fabric, aligning the edges while uncurled, trimming said uncurled edges of the fabric, and securing the edges together to form a tube while maintaining the edges uncurled and in alignment.

9. The method of modifying flattened tubular knitted fabrics to avoid the helical pattern of the design thereon which comprises, advancing the flattened fabric continuously, slitting the fabric at one side to provide separated edges, causing one layer of the fabric to follow an elongated path with reference to the path of the opposing layer to bring the design on the separated edges into register, adjusting the length of the elongated path to compensate for variations in register, progressively uncurling the edges of the fabric, aligning the edges while uncurled, trimming said uncurled edges of the fabric, and securing the edges together to form a tube while maintaining the edges uncurled and in alignment.

10. In an apparatus for modifying flattened tubular knitted fabric, the combination of a frame, means thereon for advancing the flattened fabric continuously, means for slitting the fabric at one side to provide separated edges, means for causing one layer of the fabric to follow an elongated path with reference to the path of the other layer to bring the design on the separated edges into register, and means for sewing the edges together.

11. In an apparatus for modifying flattened tubular knitted fabric, the combination of a frame, means thereon for advancing the flattened fabric continuously, means for slitting the fabric at one side to provide separated edges, means for causing one layer of the fabric to follow an elongated path with reference to the path of the other layer to bring the design on the separated edges into register, including a pair of separated rollers and means for sewing the edges together.

12. In an apparatus for modifying flattened tubular knitted fabric, the combination of a frame, means thereon for advancing the flattened fabric continuously, means for slitting the fabric at one side to provide separated edges, means for causing one layer of the fabric to follow an elongated path with reference to the path of the other layer to bring the design on the separated edges into register, including a pair of separated rollers and means for adjusting the angular position of the rollers, and means for sewing the edges together.

13. In an apparatus for modifying flattened tubular knitted fabric, the combination of a frame, means thereon for advancing the flattened fabric continuously, means for slitting the fabric at one side to provide separated edges, means for causing one layer of the fabric to follow an elongated path with reference to the path of the other layer to bring the design on the separated edges into register, means for flattening the separated edges, including a traveling belt adapted to en-

gage the edges of the advancing fabric, and means for sewing the edges together.

14. In an apparatus for modifying flattened tubular knitted fabric, the combination of a frame, means thereon for advancing the flattened fabric continuously, means for maintaining substantially uniform longitudinal tension on the advancing fabric, means for slitting the fabric at one side to provide separated edges, means for causing one layer of the fabric to follow an elongated path with reference to the path of the other layer to bring the design on the separated edges into register, and means for sewing the edges together.

15. In an apparatus for modifying flattened tubular knitted fabric, the combination of a frame, means thereon for advancing the flattened fabric continuously, means for maintaining substantially uniform longitudinal and transverse tension on the fabric, means for slitting the fabric

20 at one side to provide separated edges, means for causing one layer of the fabric to follow an elongated path with reference to the path of the other layer to bring the design on the separated edges into register, and means for sewing the edges together.

25 16. In an apparatus for modifying flattened tubular knitted fabric, the combination of a frame, means thereon for advancing the flattened fabric continuously, means for slitting the fabric at one side to provide separated edges, means for relatively adjusting the separated edges to bring the design on the separated edges into register, and means for securing the edges together.

30 17. In an apparatus for modifying flattened tubular knitted fabric, the combination of a frame, means thereon for advancing the flattened fabric continuously, means for maintaining substantially uniform longitudinal tension on the advancing fabric, means for slitting the fabric at one side to provide separated edges, means for relatively adjusting the separated edges to bring the design on the separated edges into register, and means for securing the edges together.

35 18. In an apparatus for modifying flattened tubular knitted fabric, the combination of a frame, means thereon for advancing the flattened fabric continuously, means for maintaining substantially uniform longitudinal and transverse tension on the advancing fabric, means for slitting the fabric at one side to provide separated edges, means for relatively adjusting the separated edges to bring the design on the separated edges into register, and means for securing the edges together.

40 19. In an apparatus for modifying flattened tubular knitted fabric, the combination of a frame, means thereon for advancing the flattened fabric continuously, means for slitting the fabric at one side to provide separated edges, means for relatively adjusting the separated edges to bring the design on the separated edges into register, and means for flattening the separated edges including a traveling belt adapted to engage the edges of the advancing fabric, and means for sewing the edges together.

45 20. In an apparatus for modifying flattened tubular knitted fabric, the combination of a frame, means thereon for advancing the flattened fabric continuously, means for slitting the fabric at one side to provide separated edges, means for causing one layer of the fabric to follow an elongated path with reference to the path of the other layer to bring the design on the separated edges into register, belt means for uncurling the open

edges of said fabric and stitching means adjacent said uncurling means for stitching said open edges together and forming a tube.

21. In an apparatus for modifying flattened tubular knitted fabric, the combination of a frame, means thereon for advancing the flattened fabric continuously, means for slitting the fabric at one side to provide separated edges, means for relatively adjusting the separated edges to bring the design on the separated edges into register, belt means for uncurling said fabric edges and temporarily maintaining said edges in flat form, and stitching means adjacent said uncurling means for stitching said open edges together and forming a tube.

22. In an apparatus for modifying flattened tubular knitted fabric, the combination of a frame, means thereon for advancing the flattened fabric continuously, means for maintaining substantially uniform longitudinal tension on the advancing fabric, means for slitting the fabric at one side to provide separated edges, means for relatively adjusting the separated edges to bring the design on the separated edges into register, belt means for uncurling said fabric edges and temporarily maintaining said edges in flat form, and stitching means adjacent said uncurling means for stitching said open edges together and forming a tube.

23. Apparatus for uncurling the edges of a traveling strip of fabric consisting of equal superposed plies of fabric with free edges including a belt disposed between the plies having substantially straight portions traveling outward at a side of said strip and engaging the curled portions of the edges of the two plies, said belt having friction creating surfaces, and means for driving said belt so that belt surfaces engaging the fabric plies travel in a direction transverse to the path of the fabric strip.

24. Apparatus for uncurling the edges of a traveling strip of fabric consisting of equal superposed plies of fabric with free edges, said apparatus including a belt disposed between the plies having substantially straight portions traveling outward and simultaneously engaging upper and lower plies of said fabric respectively, and means for driving said belt so that said portions engaging the fabric travel in a direction transverse to that of the fabric strip.

25. Apparatus for uncurling the edges of a traveling strip of fabric consisting of equal superposed plies of fabric with free edges including belt means disposed between the plies, one run of the belt means engaging the fabric, a plate separating

the other run of the belt means from the fabric, said belt means being driven at high speed and flattening the fabric edges passing thereover.

26. Apparatus for uncurling the edges of a traveling strip of fabric consisting of equal superposed plies of fabric with free edges, means for uncurling and sewing said free edges consisting of a friction belt having one run engaging said fabric between the two plies and moving in a direction transverse to the line of travel of said fabric to uncurl the upper and lower plies of said fabric at said open edges and temporarily to maintain said edges in flat form, a plate separating the other run of the belt from the fabric and stitching mechanism adjacent said belt for stitching said open edges together and forming a tube.

27. The method of modifying flattened tubular knitted fabric which comprises advancing the flattened fabric continuously, cutting the fabric at one side to provide separated edges, relatively adjusting the edges of the fabric to bring the design into register and securing the separated edges so that the fabric is restored to tubular form.

28. The method of modifying flattened tubular knitted fabric which comprises advancing the flattened fabric continuously while maintaining substantially uniform longitudinal and transverse tension on the fabric, cutting the fabric at one side to provide separated edges, relatively adjusting the edges of the fabric to bring the design into register and securing the separated edges so that the fabric is restored to tubular form.

29. The method of modifying slit tubular knitted fabric which comprises advancing the slit fabric continuously, relatively adjusting the edges of the fabric to bring the design into register and securing the separated edges so that the fabric

40 is restored to tubular form.
